UNITED STATES PATENT OFFICE.

EDWARD J. DOLAN, OF PHILADELPHIA, PENNSYLVANIA, ASSIGNOR TO
WILLIAM HACKER, TRUSTEE, OF SAME PLACE.

CAN-MAKING MACHINE.

SPECIFICATION forming part of Letters Patent No. 371,493, dated October 11, 1887.

Application filed March 23, 1887. Serial No. 232,165. (No model.)

To all whom it may concern:

Be it known that I, EDWARD J. DOLAN, a citizen of the United States, residing at Philadelphia, in the county of Philadelphia and State 5 of Pennsylvania, have invented certain new and useful Improvements in Can-Making Machines; and I do hereby declare the following to be a full, clear, and exact description of the invention, such as will enable others skilled in 10 the art to which it appertains to make and use the same, reference being had to the accompanying drawings, and to letters and figures of reference marked thereon, which form a part of this specification.

15 Like letters and figures refer to the same parts throughout the several views.

This invention relates to can-making machines; and it has for its object to provide an 20 organized machine, in which the blanks fed in at one end are turned out in the form of completed cans, the steps necessary to the formation of such cans following each other in rapid succession in one and the same machine. The 25 novelty lies in the peculiar combinations and the novel construction, arrangement, and adaptation of parts, whereby the desired end is accomplished, all as more fully hereinafter described and claimed.

In the accompanying drawings I have found 30 it necessary, in order to properly illustrate my device, to represent the same upon such a scale as to require the separation of some of the views. Consequently, in some cases, two 35 sheets of drawings will have to be looked upon as constituting but a single figure. For instance, Figures 1 and 1^a represent a side elevation, partly in section, of a can-making machine constructed in accordance with my invention. Figs. 2 and 2^a indicate a top plan of 40 the same. Fig. 3 is a sectional detail of the seaming device, more particularly hereinafter referred to. Fig. 4 is a sectional detail, on a horizontal plane, of the feeding and expanding devices. Fig. 5 is a cross-section on line 45 x x of Fig. 4, showing, also, the construction and operation of the clamping-jaws. Figs. 6 and 7 are a plan and side view, respectively, of a portion of the mechanism for placing and soldering the tops and bottoms of the cans. 50 Figs. 8 and 9 are plan views of a continuation of the same. Fig. 10 is a detail side view of the soldering-hopper mechanism. Fig. 11 is

a detail section of one of the can-holding clamps. Fig. 12 is a detail section of the mechanism employed for supplying gas and 55 air to the soldering-irons. Fig. 13 is a cross-section through the die-operating mechanism. Fig. 14 is a detail in end elevation of the jaws H'.

Referring to the details of the drawings, A 60 designates the base of the main frame, rising from the extreme front end of which are the standards a, in which is journaled the transverse shaft A', carrying the pulleys A².

Journalized in suitable boxes on the rearward 65 projections, a', of the standards A³, which rise from the base-plate, is the transverse shaft A⁴, carrying the pulleys A⁵, around which and the pulleys A⁶ pass the endless conveyers or chains 70 A⁷, provided at regular intervals with projections a⁸, for a purpose hereinafter explained.

Upon the outer end of the shaft a⁴ is the pulley a⁹, around which and the pulley a¹⁰, carried by the shaft A¹, suitably journalized in 75 boxes upon the front face of the standards A³, passes the endless chain a¹¹. Upon this shaft A¹ are also secured the pulleys a¹², around which and the pulleys a¹³ upon the shaft A⁸, secured in suitable boxes on the arms A⁹, toward the rear of the machine, pass the endless conveyers or chains a¹⁴, provided with 80 projections similar to those upon the conveyers a⁸, just described.

Motion is imparted to the shaft A' by means 85 of the drive-pulley A¹⁰ on said shaft, and designed to be connected with any suitable source of power, (not shown;) or, if preferred, the said conveyer may be operated from the shaft C³ by means of the connections shown in 90 dotted lines in Fig. 1, in which 30 is a pawl engaging a ratchet-wheel, 31, on the shaft A⁴, said pawl being operated by suitable connections with the shaft C³, as shown.

The blanks B, which have been previously 95 stamped out by a suitable die, which cuts out the covers, leaving openings b at opposite ends, as shown in Fig. 2, are placed upon the conveyers A⁷, the projections a⁸ of which engage said openings, as shown in said Fig. 2. These 100 blanks are carried along by said conveyers until they arrive beneath the cutting-die C. This die is carried by a cross-head, C', suitably guided in the guides c on the standards A³ and

operated by suitably-timed cams C² upon the transverse shaft C³, journaled in the standards A³. Beneath this die, suitably supported by said standards, is the female die or block B'. 5 The conveyers A⁶ pass between the top of this female die and the projections b', formed on or attached to the standards A³, which projections are for the purpose of preventing the blanks from being carried upward by the die 10. After the blanks forming the can-bodies have been cut from the blanks B. These blanks as they are cut fall through the opening in the female die onto the conveyer a⁸, to which motion is imparted through the medium of the 15 pulleys a³ a⁴ and the chain a⁵.

To impart an intermittent motion to the conveyer a⁸, I have provided the following mechanism: Upon the end of the shaft A¹, I secure a ratchet-wheel, D, and upon the corresponding 20 end of the shaft C³, I secure a heart-shaped cam, C⁴. Pivoted to the standards A³, at this side of the machine, is a bell-crank lever, D', one end of which carries a pin, d', working in the cam-groove in the cam C⁴, while to the end 25 of the other arm of this bell-crank is pivotally secured the lever D², formed with or carrying at its free end a pawl, d², engaging said ratchet-wheel.

D³ is a spring connecting the adjacent ends 30 of the lever D² and the arm of the bell crank, to which it is pivoted.

Any suitable means may be provided for conveying off the scrap-tin from the conveyer A⁶ to prevent its falling upon the conveyers a⁸. 35 In the drawings I have shown one means, which consists of a table, 32, secured to the frame of the machine in such a position as to receive the refuse or scrap-tin from the conveyer; but while I have shown this form I do not intend 40 to limit myself thereto, as it is evident that various other means may be provided for this purpose without departing from the spirit of my invention.

Rising from the bed-plate are the standards 45 E, in the upper ends of which is journaled the shaft E', carrying the pulley E², connected by suitable belt or chain with the wheel E³ on the shaft C³, as shown in dotted lines. Upon this shaft E' is the cam E⁴, shaped to operate the 50 seaming-die E⁵ at stated intervals. This seaming-die is operated substantially in the same way as that shown and described in my patent, No. 353,737, dated December 7, 1886, but is constructed differently in the following particulars: The die proper, e, is of usual construction. The die E⁵ is recessed vertically, as shown at e', and within this recess, at the lower end thereof, is pivoted the die-holder e², with its bent end e³ slotted, as shown at e⁴, in which is 55 removably and adjustably secured the die e⁶, which, it will be observed, is set at an angle to the die proper, e. The upper end of this die-holder is attached to or connected with a sliding plate, e⁵, moving in suitable guides on 60 the top of the die, and provided with a pin, e¹, working in a cam-groove, e⁸, in the cam E' on the shaft E', all so timed that as the die de-

scends the supplemental die e⁶ is forced downward at an angle to force the tin into the angular notch 33, after which it is compressed by 70 means of the hammer E⁸, fully described in the patent above referred to.

The can-body blanks are clamped around the mandrel F by means of clamping-jaws F', which are similar to and operated in the same manner 75 as those described in my patent, No. 345,284, dated July 13, 1886, and therefore need not be further illustrated or described in this application.

The mandrel F, a cross section of which is 80 shown in Fig. 5, to which, and to Fig. 4, especial attention is now directed, is at its front end cored out, as at f, and upon its side is provided with an undercut groove, f', in which the bar f² is reciprocated by the mechanism shown and described.

In order to expand the cylinder before it has been operated upon by the die, in the manner above described, so as to allow it to move freely upon the mandrel, and to provide sufficient metal for forming the seam, I place within the cored-out portion of said mandrel a rod, F², provided upon its inner end with the eccentric pin F³. This pin engages the bifurcations f³ of the arm F⁴, secured to the shaft F⁵, which is suitably journaled within a recess formed in the under side of the mandrel. This shaft carries the wing or segmental arm F⁶, which, when in its normal position, in which position it is represented in Fig. 5, forms or 100 completes the circular form of the mandrel, as shown in said figure. The outer end of this rod F² has rigidly secured to it one end of the connecting-rod F⁷, the opposite end of which is pivotally connected to the vertical connecting-rod F⁸, which is made adjustable, preferably as shown in the drawings, in which it is represented as composed of two parts connected together by a turn-buckle or adjusting-screw. The opposite end of this link F⁸ is pivotally connected to one end of the lever F⁹, 110 fulcrumed at f⁴ on the lug f⁵, projecting from the standard E near its base. The opposite end of this lever is provided with a pin, f⁶, working in the cam-groove f⁷ of the cam f⁸, 115 which cam is operated from the shaft E' by means of the rod F¹⁰, cam F¹¹ on the shaft E', and the intermediate connections shown, all so timed as to rock the shaft F² and cause the wing F⁶ to be thrown outward, as shown in dotted lines in Fig. 5, which slightly expands the tin and tightens or draws together the seam. The outer end of the sliding bar f² has 120 pivotally connected to it at one end the lever f⁹, fulcrumed at f¹⁰ on the lug f¹¹ on the front face of the standard E. The opposite end of this lever is pivotally connected, as at f¹², to the rod f¹³, the opposite end of which is pivoted to the rod F¹⁰, so that the cam f⁸ serves to operate the expander. The rod f¹³ serves, 130 by reason of its connection with the rod f¹⁰, through the medium of the intermediate mechanism above described, to throw forward the bar f², which, by reason of the engagement of

its lug or catch f^{14} , pushes forward the cylinder on the mandrel, so that it may be operated upon by the hammer E^s .

After the cylinder or can-body has been operated upon by the hammer it is ready to be soldered, and is pushed along upon the mandrel to the soldering device by the next succeeding cans, which are moved along automatically by the mechanism above described.

10 The soldering device consists of the hopper G , suitably supported upon the arm G' , attached to the bracket g , rising from the arm A^9 , in which hopper pulverized resin and solder are placed. The hopper is preferably of 15 the form shown and described in my patent, No. 359,962, dated March 22, 1887. The distributor is connected to the cam g^2 upon the shaft g^3 , which latter derives its motion from the shaft A^8 by means of the pulleys g^4 g^5 and 20 suitable belt, g^6 . The rotation of the shaft g^3 operates the cam g^2 and causes the distributor to be reciprocated, thus sprinkling evenly the solder and resin upon the seam of the cans, which pass directly beneath the discharge- 25 outlet of said hopper. Suitably supported upon the standard G^2 , rising from the arm A^9 , is the soldering-iron G^3 , heated in any suitable way and capable of adjustment by means of the arm G^4 and adjusting device G^5 ; but as this 30 is a well-known expedient in can-making machines a further description will not be necessary. The can-cylinders are fed forward from beneath the soldering-hopper by means of the chain G^6 , passing over the pulleys G^7 , operated 35 from the shaft A^8 by means of the pulleys g^7 and g^8 and belt g^9 . This belt G^6 is provided with projections similar to those above described upon the other belts, which projections engage the rear ends of the cams and force 40 them forward. The can-bodies are now ready to receive the heads or tops and bottoms, the process of placing and soldering which is executed automatically in the following manner:

Secured upon the overhanging arm H are 45 the guides h , through one of which passes the spring-finger h' , provided at its extreme end with a hook, h^2 . Hinged to the guides h are the jaws H' , which when united form a semi-cylinder of proper size to receive the can-body, 50 and so constructed as to loosely hold the same, but to open and allow the same to drop when any additional weight is brought to bear thereon. This additional weight I prefer to apply in the following manner: Rising from 55 the overhanging arm H is the casting H^2 , formed with sockets h^3 , which serve as guides for the vertical shaft H^3 , carrying the curved plunger H^4 . Journaled upon this casting is the cam H^5 , which derives its motion by a belt 60 from the shaft E' , as shown in dotted lines, Fig. 1^a. h^4 is a lever fulcrumed at h^5 on the casting H^2 , one end of said lever being pivotally connected with the finger h' and its other end carrying a pin, h^6 , working in the cam- 65 groove h^7 of the cam H^5 . h^8 is another lever fulcrumed at one end to the casting H^2 and at its other end pivoted to the link h^9 , the other

end of the link being attached to the shaft H^3 . H^6 is a pin attached to the lever h^8 and working in the groove h^7 of the cam H^5 . These parts 70 being so arranged and timed that as the plunger H^4 descends upon the can-body and causes the jaws H' to open, the finger h' is thrown forward to grasp another can, and as the plunger ascends the said finger moves in 75 the opposite direction and brings the next can-body into the jaws, which in the meantime have been brought back into their normal position by the springs h^{10} , provided and arranged for this purpose. As the can is released by the jaws H' , it falls upon suitably-constructed carriers carried by an endless chain arranged to travel at right angles to the direction in which the blanks travel during 80 the operation above described. This chain 85 and the mechanism pertaining thereto, constituting the conveyer for the completed bodies, is clearly illustrated upon Sheets 5, 6, and 7 of the drawings, to which special attention is 90 now called.

I is a shaft journaled in suitable bearings (not shown) and carrying the drive-wheel I' and sprocket-wheel I^2 , to which motion is imparted from any suitable source of power. Passing around this sprocket-wheel, and also 95 around a similar wheel (not shown) at the other end of the track, is an endless chain made up of the links I^4 , provided with eyes i^6 and having lateral flanges i^5 , which move in parallel horizontal guides i^4 . These links are 100 provided at either end with a lug, I^5 , between which lugs is secured by a hinged connection, as shown at i^7 , the tilting can-carrier I^6 . The sprocket-wheel I^2 is provided with a peripheral channel or groove i , within which travel 105 the rollers i upon the under side of the tilting can-carrier I^6 . The track, which extends upon a horizontal plane upon a straight line, is suitably supported upon supports i^8 , or in any other desirable way, and is formed of the bed i^9 , in 110 which the rollers i are guided, and the parallel horizontal guides i^4 , in which move the lateral guides i^5 on the endless chain I^4 . This prevents the chain and can-carrier carried thereby 115 from deviating from a straight line, and thus insures the can being presented to the soldering 120 devices in the exact position desired.

The can-carriers I^6 —one of which is shown in section in Fig. 11—are pivotally secured between lugs I^5 on the links I^4 , by means of suitable screws, as shown at i^7 , or by other hinged connection, so as to allow the carriers to tilt in a direction at right angles to the line of the endless chain, for a purpose which will hereinafter be more fully explained.

125 The tilting can-carrier I^6 is provided with arms or extensions i^8 , and to the upper ends of these arms are pivotally attached the lower ends of the clamping-wings I^9 , provided upon their outer faces with the projections i^9 . Within the hollow interior of the upright portion of the casting I^6 is arranged the hollow shaft I^8 , within the lower end of which is journaled the roller i . The upper portion of the 130

shaft I^8 is of less diameter than the lower portion, thus forming the shoulder i^{10} , against which bears the spring i^{11} , arranged within a suitable chamber above the shoulder, while within a suitable chamber within the foot of the shaft is arranged the spring i^{12} , having a bearing against the upper face of the plate i^{13} . The arms i^9 upon the wings L^1 are connected to the casting K , secured to the base of the shaft I^8 by means of the connecting-links K' . Within the lower part of the clamping portion of the can-holding chamber are arranged suitable projections or pins, k , which, when the clamping-jaws are closed, bear against the surface of the can-body near its ends.

k' is a concave piece of metal secured to the upper end of the adjustable shaft I^8 and serves to slightly raise the can-body when the clamping-jaws are opened, and thus allow the same to freely revolve during the process of soldering the end seams.

At the ends of the tilting can-carrier, and suitably journaled within brackets or extensions K^2 , are the wheels K^3 , which, when in their normal or horizontal position, serve as brackets or shelves for the reception of the can-tops and bottoms before the same are clamped in position upon the can-bodies.

From the foregoing description it will be clearly understood that when the tilting can-carrier is in its normal position upon the track the jaws will be closed, and that they will be opened only when the wheel i' reaches a depression in the track upon which it travels. It will also be apparent that the normal position of the body of the tilting can-carrier is horizontal, and that it is adapted to be tilted in either direction upon occasion of the wheels K^3 reaching an inclined guiding or tilting track—such as that shown at K^4 —in order that the end may be properly presented to the soldering-irons.

When, therefore, the can-carrier reaches the position beneath the delivery-clamps above described, in connection with that portion of the machine in which the bodies are formed, the wheel i' rests upon a depression, 90, in the track and the clamping-jaws are opened. Upon the forward movement of the carriage the wheel i' leaves the depression and the jaws are clamped around the can-body. An attendant upon each side of the conveyer places upon the wheels or shelves K^3 the blanks for the tops and bottoms of the cans, the edges of which are turned slightly, so as to permit of their being placed in position over the ends of the can-bodies, which is done by attendants stationed at proper intervals along the sides of the conveyer. When the can-carrier, in the course of the travel of the endless chain, reaches the point at which it is desired to distribute along the end seams the pulverized soldering material, the jaws are caused to open by reason of the wheel i' reaching a depression in the track, and the can within the chamber, through the mechanism above described in connection with the description of the car-

riage, is lifted from its contact with the pins k and caused to revolve by reason of contact of the wheels K^3 with the track K^4 . A suitable heating apparatus (not shown) is provided beneath the traveling can, in advance of the soldering device, for heating the can in order to retain the solder upon the seam.

The solder is distributed upon the end seams of the can in the following manner: The soldering mechanism L , which is shown in cross-section in Fig. 10 of the drawings, consists of a series of hoppers, L^1 , arranged upon suitable supporting-arms, L^2 , which are carried by the endless chain L^3 within the frame L^4 , placed in such a position as to cause the hoppers to pass directly above the cans as they revolve within the open chambers of their respective carriages. Suitable openings within the bottoms of the hoppers are provided, which openings correspond relatively with the positions of the end seams of the cans to be soldered. The apertures in the bottoms of the hoppers are adapted to be opened and closed by means of a suitable bar or plate passing through the hopper above the openings and provided with holes corresponding with the openings in the bottom of the hopper. This plate is reciprocated at the proper time by means of the pinions l upon the post L^2 , (which it is connected with by suitable crank mechanism,) coming in contact with the rack-bar l' , secured upon the main frame of the device. Power is transmitted to the endless conveyer L^3 by means of the shaft M and suitable train of gearing, as shown at M^1 , M^2 , M^3 , &c. After receiving the soldering material from the hoppers, as above described, the can is in readiness for the final process of soldering, which will be readily understood by reference to Figs. 6, 7, 8, and 9 of the drawings, in connection with the foregoing description of the general construction and operation of the endless chain and tilting can-carriers carried thereby.

The soldering device proper consists of a series of hollow soldering-irons, N , suitably supported upon brackets upon a frame, N' . This supporting-frame is in all respects similar to the supporting-frame used in connection with the soldering-hoppers above described, excepting that the rack-bar is dispensed with and adjustable arms or brackets for supporting the soldering-irons N^2 are substituted in their stead.

As to the means for supplying air and gas to the soldering-irons, attention is directed to Fig. 12 of the drawings, in which I have shown upon an enlarged scale a vertical section of the apparatus used.

N^3 is the main central shaft, upon the upper end of which is placed the enlarged portion P , provided with the upper and lower chambers, P^1 , P^2 , having openings p , p' . Secured to the ceiling is the bracket P^3 , journaled within which is the upper end of the hollow shaft or pipe P^4 , which communicates at its lower end with the interior of the lower chamber, P^2 .

P^5 is an outer pipe of slightly greater diameter than the inner pipe, P^1 . It closely fits at its ends about the pipe p^4 , and is provided at a point near its upper end with an inlet-pipe, 5 p^2 , and has openings near its lower ends which communicate with the interior of the upper chamber, P' . Gas is admitted to the lower chamber, P^2 , through the pipe P^4 , and is conveyed to the interior of the soldering-irons by 10 means of the pipe R , and air is supplied from the chamber P' by means of the pipes S , which are extended through the interior of the pipe R , as shown.

As the mechanism for operating the soldering devices is unimportant and forms no part 15 of my invention, and, further, as it is in all respects similar to that used in connection with the solder-distributing mechanism, a detailed description of the same in this connection 20 is not deemed necessary.

The tilting can-carrier having, upon its arrival beneath the first of the soldering devices, been properly tilted by means of the cam-track, suitably placed, as shown, so that 25 the seam at one end of the can passes directly beneath the soldering irons, the seam is thus soldered. In order to solder the seam at the other end of the can, the can-carrier is tilted in the opposite direction above the other soldering device by means of the cam-track suitably 30 arranged upon the other side of the endless chain.

Various modifications in detail may be made 35 without departing from the spirit of my invention.

Having thus fully described my invention and set forth its merits, what I claim to be new, and desire to secure by Letters Patent, is—

40 1. An organized machine for the manufacture of tin cans, comprising a mandrel, a side-seamer, a side-seam solderer, means for moving the can-bodies from the side-seamer to the side-seam solderer, a conveyer for the completed can-bodies, mechanism for clamping the tops and bottoms to said can-bodies, means for transferring said bodies to the end-clamping mechanism, and means for operating the several devices in due order, substantially as described.

45 2. An organized machine for the manufacture of tin cans, comprising a mandrel, a side-seamer, an expander, a side-seam solderer, means for conveying the can-bodies from the side-seamer to the side seam solderer, a conveyer for the completed bodies, mechanism for clamping the tops and bottoms to said bodies, means for transferring said bodies to the end-clamping mechanism, and means for 50 operating the several devices in due order, substantially as described.

55 3. An organized machine for the manufacture of tin cans, comprising a mandrel, a side-seamer, a side-seam solderer, means for moving the blank from the side-seamer to the side-seam solderer, a conveyer for the completed

can-bodies, means for automatically clamping the tops and bottoms to said bodies, means for transferring the bodies to said clamping means, and means for operating the several devices in 70 due order, substantially as described.

4. An organized machine for the manufacture of tin cans, comprising a mandrel, a side-seamer, an expander, a side-seam solderer, means for moving the blank from the side-seamer to the side-seam solderer, a conveyer for the completed bodies, means for transferring the bodies from the mandrel to the conveyer, means for automatically clamping the tops and bottoms to said bodies during the 80 travel of said conveyer, and means for operating the several devices in due order, substantially as described.

5. An organized machine for the manufacture of tin cans, comprising a mandrel, a side-seamer, a side-seam solderer, means for moving the blanks from the side-seamer to the side-seam solderer, an endless conveyer for the completed bodies arranged at right angles to the travel of the can-blanks during the 90 formation of the bodies, means for transferring the bodies from the mandrel to the conveyer, and means for operating the several devices in due order, substantially as described.

6. An organized machine for the manufacture of tin cans, comprising a mandrel, a side-seamer, a side-seam solderer, means for moving the blanks from the side-seamer to the side-seam solderer, a conveyer for the completed bodies, means for transferring the bodies from 95 the mandrel to the conveyer, means for automatically clamping the tops and bottoms to said bodies during the travel of said conveyer, and a soldering device for soldering said tops and bottoms in place, and means for operating 100 the several devices in due order, substantially as described.

7. An organized machine for the manufacture of tin cans, comprising a mandrel, a side-seamer, a side-seam solderer, means for moving the blanks from the side-seamer to the side-seam solderer, a conveyer for the completed bodies, means for transferring the bodies from the mandrel to the conveyer, means for automatically clamping the tops and bottoms to 110 said bodies, and a rotating soldering device 115 for soldering the same in place, and means for operating the several devices in due order, substantially as described.

8. An organized machine for the manufacture of tin cans, comprising a mandrel, a side-seamer, an expander, a side-seam solderer, means for moving the blanks on said mandrel to said devices successively, spring-actuated jaws for holding the completed bodies, a conveyer for the completed bodies passing beneath said spring-actuated jaws, means for transferring the bodies from the mandrel to said jaws, means for transferring the bodies from said jaws to the conveyer, means for automatically clamping the tops and bottoms, and a soldering device for soldering said tops 125. 130

and bottoms in place, and means for operating the several devices in due order, substantially as described.

9. An organized machine for the manufacture of tin cans, comprising a mandrel, a side-seamer, a side-seam solderer, means for moving the blanks on said mandrel to said seamer and solderer, a conveyer for the completed bodies, means for transferring the bodies from the mandrel to the conveyer, automatic end-clamping devices, a rotary solder-distributing device, a rotary soldering device, and means for operating the several devices in due order, substantially as described.

10. An organized machine for the manufacture of tin cans, comprising a mandrel, a side-seamer, a side-seam solderer, means for moving the blanks from the side seamer to the side-seam solderer, a conveyer for the completed bodies comprising a tilting carrier, means for transferring the bodies from the mandrel to the conveyer, and means for operating the several devices in due order, substantially as described.

11. An organized machine for the manufacture of tin cans, comprising a blank-cutter, a mandrel, a side seamer and solderer, the conveyer A^8 , mechanism for bending the blanks into the form of a cylinder, the conveyer I^4 , mechanism for presenting the body to the above-named devices successively, and means for operating the said devices in due order, a conveyer for the completed bodies, means for transferring the bodies from the mandrel to the conveyer for the completed bodies, mechanism for clamping the tops and bottoms, and a rotary solderer for soldering said tops and bottoms, substantially as described.

12. The combination, with the mandrel, the devices for forming the can-body, means for moving the bodies along the mandrel, and the hinged jaws H' , of means for delivering the body to said jaws, a conveyer for the completed bodies, and a reciprocating plunger, H^4 , substantially as described.

13. The combination, with the mandrel, the devices for forming the can-body, the hinged jaws H' , and reciprocating plunger H^4 , of means for forcing the body along said mandrel into said jaws, and the endless conveyer for the completed bodies arranged beneath said jaws, substantially as described.

14. The combination, with the devices for forming the can-body, the mandrel F , and the hinged jaws H' , arranged at one end thereof, of means for moving the can-body along said mandrel, means for forcing it off said mandrel into said jaws, the reciprocating plunger H^4 , and the endless conveyer for the completed bodies beneath said jaws at right angles to said mandrel, substantially as and for the purpose described.

15. In a can-making machine, the combination, with the mandrel, of the devices for forming the can-body, the hinged jaws and reciprocating plunger, means for moving the can-

body along said mandrel, means for forcing it off said mandrel into said jaws, the endless conveyer for the completed bodies at right angles to said mandrel, and a suitably-timed cam for operating said plunger, substantially as and for the purpose described.

16. The combination, with the mandrel, the devices for forming the can-body, the hinged jaws and the plunger, and means for operating said plunger, of the endless conveyer for the completed bodies, arranged beneath said jaws at right angles to the mandrel, the finger h' , parallel with said mandrel, means for moving the bodies along said mandrel, and means for operating said finger, substantially as and for the purpose described.

17. The combination, with the mandrel, the devices for forming the can-body, hinged jaws, plunger, and finger, of means for operating said plunger and means for moving the can-bodies along the mandrel, substantially as described.

18. The combination, with the mandrel, the devices for forming the can-body, and the conveyer for the completed bodies at right angles to said mandrel, of the hinged jaws H' , means for moving the can-body along said mandrel, means for forcing it off said mandrel into said jaws, the springs h^{10} , and the vertically-reciprocating plunger, substantially as and for the purpose described.

19. The combination, with the devices for forming the can-body, the mandrel, conveyer for the completed bodies, and the hinged jaws at the end of said mandrel over said conveyer, of the springs h^{10} and the vertically-reciprocating plunger, means for operating said plunger, means for moving the can-bodies along the mandrel, and means for forcing them off the mandrel into said jaws, substantially as and for the purpose described.

20. In a can-making machine, the combination, with the mandrel, means for forming the can-body, the hinged jaws H' , and means for forcing said body off said mandrel into said jaws, of the casting H^2 , formed with sockets h^3 , the vertical shaft H^3 , guided by said sockets and carrying the plunger H^4 , and means on said casting for operating said plunger, substantially as described.

21. The combination, with the mandrel, means for forming the can-body, the hinged jaws H' , and casting H^2 , formed with sockets h^3 , and means for forcing the completed body off the mandrel into said jaws, of the shaft H^3 , guided by said sockets and carrying the plunger H^4 , the cam H^5 on said casting, and intermediate connections for operating said shaft, substantially as described.

22. In a can-making machine, the combination, with the mandrel, the devices for forming the can-body, the hinged jaws H' , the casting H^2 , formed with sockets h^3 , and the shaft H^3 , guided by said sockets and carrying the plunger H^4 , of the cam H^5 on said casting, 125

the finger h' , and means for operating said plunger and finger simultaneously, substantially as described.

23. In a can-making machine, the combination, with the mandrel, the devices for forming the can-body, the extension H , the guides h , secured thereto, the jaws H' , hinged to said guides, and the finger h' , working in said guides, of the casting H^2 , the shaft H^3 , working in guides on said casting and carrying a plunger, the cam H^5 on said casting, the lever H^6 , pivoted to said casting and connected with said shaft and actuated by said cam, and the lever h^4 , also pivoted to said casting and connected with the finger, and also actuated by said cam, substantially as and for the purpose described.

24. In a machine for making tin cans, an endless conveyer for the completed bodies, comprising a tilting carrier, an inclined track, a vertically-movable roller on said carriage, and means actuated by said roller for clamping a can-body, substantially as and for the purpose described.

25. In a machine for making tin cans, an endless chain, a track for the chain, a carrier secured to the chain and provided with a vertically-movable roller, and means actuated by said roller for clamping a can-body, combined with a track for the roller, and a depression in said track, substantially as and for the purpose described.

26. In a machine for making tin cans, an endless chain, a track for the chain, a carrier secured to the chain and provided with a spring-actuated roller, and means actuated by said roller for clamping a can-body, combined with a track for the roller, and a depression in said track, substantially as and for the purpose described.

27. In a can making machine, an endless chain, a track for the chain, a carrier secured to the chain and provided with pivoted clamping-jaws, means for operating said jaws, and pivoted end-clamping jaws at right angles

thereto, and means for operating said end-clamping jaws, substantially as described.

28. In a can-making machine, an endless chain, a track for the chain, a carrier secured to the chain and provided with end-clamping jaws and rollers, and a cam-guide track for said rollers, substantially as and for the purpose described.

29. In a can-making machine, an endless chain, a track for the chain, a tilting carriage secured to said chain and provided with end-clamping jaws and rollers, as described, and a cam-guide for said rollers, substantially as and for the purpose described.

30. In a can-making machine, the combination, with the track and depression therein, of an endless chain, a track for the chain, a carrier secured to the chain and provided with a vertically-movable roller, pivoted clamping-jaws, pivoted end-clamping jaws and rollers, and a cam-guide track for said rollers, substantially as and for the purpose described.

31. In a can-making machine, the combination, with a plurality of links flexibly connected together, vertically-movable guide-rollers, tilting carriers carrying said rollers, and a track for said rollers provided with depressions, as described, of pivoted clamping-jaws on said carriages, pivoted end-clamping jaws and rollers on said carriages, and a cam-guide track for said rollers, substantially as and for the purpose described.

32. The combination, with the endless chain, a track for said chain, tilting carrier pivotally secured to the links of said chain, and clamping-jaws and rollers and the cam-guide track therefor, of a rotatable soldering device, substantially as and for the purpose described.

In testimony whereof I affix my signature in presence of two witnesses.

EDWARD J. DOLAN.
